CABLE CUTTER

Harry Russell Bethune, Scotch Plains, N. J.

Application January 22, 1954, Serial No. 28,634

Term of patent 14 years

(Cl. D54—13)

To all whom it may concern:

Be it known that I, Harry Russell Bethune, a citizen of the United States, residing at Scotch Plains, in the county of Union and State of New Jersey, have invented a new, original, and ornamental Design for Cable Cutter, of which the following is a specification, reference being had to the accompanying drawing, forming part thereof, and wherein

Fig. 1 is a side elevational view of a cable cutter, showing my new design;

Fig. 2 is a top plan view thereof;

Fig. 3 is an end elevational view looking at the left of Fig. 1;

Fig. 4 is a fragmentary side elevational view showing the blades in a partly open position; and

Fig. 5 is a fragmentary side elevational view showing the blades fully open.

I claim:

The ornamental design for cable cutter, as shown.
